UNITED STATES PATENT OFFICE

OSWALD C. BREWSTER, OF CASPER, WYOMING, ASSIGNOR TO STANDARD OIL COMPANY,
OF WHITING, INDIANA, A CORPORATION OF INDIANA

BUBBLE TOWER CONSTRUCTION

Application filed February 23, 1928. Serial No. 256,366.

The present invention relates to improvements in bubble-tower construction.

The primary object is to provide a bubble-tower of simple and durable construction which will have increased efficiency in reflux condensation and which will facilitate cleaning of the apparatus.

The invention will be fully understood from the following description, illustrated by the accompanying drawings, in which—

Fig. 1 is a broken vertical view of the bubble-tower diagrammatically illustrating the apparatus in which the invention may be carried into effect; Fig. 2, a broken vertical sectional view of a portion of the bubble-tower; Fig. 3, a broken top plan sectional view, the section being taken as indicated at line 3; and Fig. 4, a detailed view in elevation of a portion of the bubble-cap employed.

Referring more particularly to the drawings, 5 indicates a bubble-tower. The bubble-tower, as shown more clearly in Figs. 2 and 3, is provided with a series of pans 6, each of which is supported in position by angle irons 7, or other suitable means. Each pan 6 is preferably recessed centrally to provide an oblong opening 8 and is provided adjacent said opening with a raised flange, or collar, 9. By means of the collar 9, the pool of liquid maintained by the pan is prevented from overflowing through the opening 8. An inlet pipe 10 is provided which serves to receive the oil overflowing into the pipe from the pan above and to discharge it at a point near the end of the oblong collar 9. A similar pipe 11 is arranged adjacent the inlet pipe and is adapted to receive the overflow in the pan and to discharge into the pan below. The pan 6 is provided with a partition 12 located between inlet pipe 10 and outlet pipe 11, thereby compelling the incoming oil to pass completely around the collar 9 to reach the outlet pipe 11.

A bubble-cap 13, similar in shape to the collar 9, but considerably larger, is adapted to be received over the collar 9. Spacers 14 are employed to separate the walls of the bubble-cap from the collar preferably on all sides except the side adjacent the inlet and outlet pipes. The walls of the bubble-cap 13

are slotted to permit vapors to pass through the cap and into the pool of liquid outside. The slots, or openings, 15, are preferably shaped somewhat like a hair-pin. Hooks, or handles, 16 may be attached to the bubble-cap 13 to aid in the removal thereof from the tower when the tower is cleaned.

To facilitate cleaning of the apparatus, the bubble-tower 5 is provided with a large man-hole 17 suitably closed with a plate 18. Upon the removal of the plate, the bubble-caps 13 may be removed therethrough, thus permitting the tower to be entered and cleaned. The tower is also provided with a feed-line 19, with a draw-off line 20, with an incoming vapor-line 21, and with a vapor draw-off line 22.

In the operation of the apparatus, oil enters the bubble-tower near the top of the tower through line 19 and flows into the top-most of the series of pans from which it overflows through pipe 10 into the pan below. Upon reaching the pan below, the oil is prevented by partition 12 from flowing directly into overflow pipe 11 and is compelled to flow in the elongated path around the bubble-cap 13 before it reaches the outlet pipe 11 on the other side of the partition. The oil then overflows through pipe 11 into the pan below where the operation is repeated. Thus, on each of the pans a pool of oil is formed and the oil received through line 19 at the top of the tower passes successively through each of the pans until it reaches the bottom of the tower where it is drawn off through line 20.

Vapors enter near the bottom of the tower through line 21 and pass up through openings 8 in pans 6, pass down through the column of oil between the collar 9 and sidewalls of the bubble-cap 13, and pass through slots 15 into the pool of liquid maintained on the pan outside. In the course of this contact with the oil, some of the heavier fractions of the vapors are condensed and carried to the base of the tower with the feed-stock. The vapors which are not condensed pass upwardly through opening 8 of the pan above and the operation is therein repeated. The vapors are drawn off at the top of the tower through vapor-line 22. These vapors include light

ends which are stripped from the descending cooling liquid.

It has been found that this type of apparatus in which the oil on each of the pans is caused to flow through an elongated path around the bubble-cap, thus progressively changing in composition as it makes contact with the vapors and condenses a portion of them, is highly efficient as a reflux condenser. 5
10 In this connection, baffles 23 may, if desired, be employed. By means of the spacers 14, a uniform pool of oil is maintained between the collar and the sidewalls of the cap 13, thus providing a substantial pool of liquid 15 through which the vapors must pass in addition to the pool of oil outside.

With the construction as shown, the apparatus may be cleaned by removing the plate 18 of the manhole 17 and hoisting there-through the oblong shaped bubble-cap 13. 20 Hooks may be inserted in the handles 16 of a bubble-cap and the bubble-cap hoisted out of position. One hook may then be removed and the bubble-cap hoisted up endwise by means of one handle through the openings in the various pans and out of the top of the bubble-tower. The bubble-caps themselves may be cleaned conveniently outside of the tower and the pans may be cleaned in position by 25 workmen entering through the manhole 17 and the openings 8 of the various pans. The arrangement of the inlet and outlet pipes and the partition at one end of the pan presents very slight obstruction and enables the 30 remainder of the pan to be cleaned with a modicum of difficulty.

It is not intended that the details of the apparatus illustrated shall be regarded as limitations upon the scope of the invention, except in so far as included in the accompanying 40 claims.

I claim:

1. A bubble tower comprising pans provided with openings, flanges adjacent said 45 openings and serving to maintain a pool of oil on said pans, inlet and outlet pipes arranged substantially in juxtaposition, partitions separating said inlet and outlet pipes, said flanges being so shaped as to cause the 50 material flowing from said inlet pipes to said outlet pipes to follow an elongated path, bubble caps provided with side openings, and adapted to be received over said flanges, and spacers separating the side walls of said 55 bubble caps from said flanges except where the inlet and outlet pipes and partitions are located.

2. In apparatus of the character set forth, a bubble tower having an opening in one end, 60 a removable closure plate for said opening, a plurality of pans each having an opening centrally disposed therein, means for maintaining a pool of liquid on said pans, and bubble caps adapted to be placed over said 65 openings, said bubble caps being of such size

and shape as to permit the removal of said bubble caps from the tower through the pan openings and the opening in the end of the tower.

3. In apparatus of the character set forth, 70 a bubble tower having an opening in one end, a removable end plate closing said opening, a plurality of pans each having an opening centrally disposed therein, flanges adjacent said openings, bubble caps adapted to be received over said flanges, spacers separating said flanges and bubble caps, said bubble caps being of such size and shape as to permit of their removal through said pan openings and said opening in the end of the tower. 75
80

4. In apparatus of the character set forth, 85 a bubble tower having an opening in one end, a closure plate adapted to close said end, a plurality of pans each having an opening centrally disposed therein, flanges adjacent said 90 openings, bubble caps adapted to be received over said flanges, inlet and outlet pipes, and partitions separating said inlet and outlet pipes, said bubble caps being of such size and shape as to permit of their removal through said pan openings and the opening in the end of the tower.

5. In apparatus of the character set forth, 95 a bubble tower having an opening in one end, a closure plate adapted to close said end, a plurality of pans each having an opening centrally disposed therein, flanges adjacent said 100 openings, bubble caps adapted to be received over said flanges and also being of such size and shape as to permit their removal through said pan openings and the opening in the end of the tower, inlet and outlet pipes arranged substantially in juxtaposition, and partitions separating said inlet and outlet pipes.

6. A bubble tower comprising, pans provided with openings, flanges adjacent said 105 openings and serving to maintain a pool of oil on each of said pans, inlet and outlet pipes arranged substantially in juxtaposition, partitions separating said inlet and outlet pipes, said partitions cooperating with said flanges to cause the material flowing from said inlet 110 pipes to said outlet pipes to follow an elongated path, bubble caps provided with side openings and adapted to be received over said flanges, and spacers separating the side walls of said bubble caps from said flanges. 115

In testimony whereof I have hereunto set my hand this 16th day of February, 1928.

OSWALD C. BREWSTER.
